UNITED STATES PATENT OFFICE.

ELIE JOSEPH VERMEYEN, OF CHOISY-LE-ROI, FRANCE.

CONTINUOUS-DISTILLATION DEVICE.

Application filed April 11, 1922. Serial No. 551,727.

To all whom it may concern:

Be it known that I, ELIE JOSEPH VERMEYEN, a subject of the King of the Belgians, residing at 9 Rue Thiers, Choisy-le-Roi, France, have invented a new and useful 5 Continuous-Distillation Device, of which the following is a specification.

This invention relates to a continuous 10 distillation device, and has for its object to provide a device adapted for the continuous production of distillation gases and for the continuous combustion beneath the grate of the distillation gases produced.

This invention has also for its object the 15 provision of a continuous distillation device adapted for the production of heat which may be utilized for heating water or for other purposes.

This distillation device comprises essen- 20 tially a body of cylindrical or any other appropriate form, having its base widened and pierced with openings forming holes through which the gases of combustion es- cape and are conducted to the chimney.

25 In the accompanying drawings, which show by way of example a form of the invention;

Figure 1 is a vertical section of a small 30 boiler provided with a distillation device and

Figure 2 is a plan view of the device shown in Figure 1.

The distillation furnace according to the 35 invention comprises essentially three parts: first the base A, in which combustion takes place; second the reservoir B for the combustible material, in which the distillation takes place; and third the conduit C for the gases of distillation.

40 The base has the form of a truncated cone and rests at its greatest diameter upon the grate N. This widening towards the base is intended to prevent the cinders from slipping into the flues E. The wall of 45 the base A is pierced with openings or holes through which the gases of combustion pass, and are then eliminated by the circular flue E, the collector G and the chimney F'. The dimensions of the perforated portions de- 50 pends upon the size of the device and the kind of stove, boiler, furnace or other heating device to which the distillation furnace is adapted; that is to say the total surface of these holes is to be calculated for each 55 specific application of the invention, slightly greater than the total surface of the open-

ings in the grate N upon which the base A rests.

The reservoir for combustible material, or still B forms the immediate extension of 60 the base A described above. The section of the body B necessarily depends upon the particular application of the invention, and it is by way of example only that the body shown in the drawings is of cylindrical 65 form, and has its upper part extended in the form of a funnel so that it touches the inner wall of the boiler and forms the circular flue E which prevents the gases of com- 70 bustion from becoming mixed with the gases of distillation.

The upper part of the reservoir D is 75 closed by a cover and any device may be applied to admit the introduction of combustible material without freeing a passage for the escape of the gases of dis- 80 tillation. Care must be taken not to fill the space D which is necessary for the gases of distillation.

Finally, the third part comprises the 85 conduit C which leads the gases of distillation beneath the grate N. The gases of distillation are mixed with fresh air introduced through the fresh air inlet K and pass 90 through the bed of ignited combustible material where they are transformed into carbon-dioxide, thus producing an increase of calories. In the other cases the conduit C will serve for carrying the gases of distillation to special apparatus for other uses. 95

To start the distillation device, the in- 100 ventor ignites the fuel in the container B by means of some easily ignited material such as paper and wood, placed upon the grate A before the container B is charged with fuel.

In the drawing, H represents the space between two cylindrical walls of the boiler which contains water and into which pass two pipes, J and J' for circulating the water 105 contained in the said space after the principle of the thermo-siphon.

I claim:—

1. A continuous distillation device com- 110 prising a distillation vessel having a grate, an outwardly flaring frusto-conical lower end on said distillation vessel resting on said grate, a chimney, openings in the out- wardly flaring lower end of said distilla- tion vessel communicating with said chimney, and means for leading the gases of distillation from said distillation vessel to a

point beneath said grate and for drawing in air for combustion of said gases beneath said grate.

2. A continuous distillation device comprising a distillation vessel having a grate, an outwardly flaring frusto-conical lower end on said distillation vessel resting on said grate, a chimney, openings in the outwardly flaring lower end of said distillation vessel communicating with said chimney, an air inlet beneath said grate, an annular gas inlet surrounding said air inlet, and a conduit for leading the gases of distillation from said distillation vessel to said air inlet.

3. A continuous distillation device comprising a distillation vessel having a grate, an outwardly flaring frusto-conical perforated base on said distillation vessel resting on said grate, an outwardly flaring frusto-conical upper end on said distillation vessel, a chimney, an annular flue surrounding said distillation vessel defined vertically by said frusto-conical base and said frusto-conical upper end and communicating with said chimney, a conduit for leading the gases of distillation from said distillation vessel to a point beneath said grate and means for drawing in air for combustion of said gases beneath said grate.

4. A continuous distillation device comprising a distillation vessel having a grate, an outwardly flaring frusto-conical perforated base on said distillation vessel resting on said grate, an outwardly flaring frusto-conical upper end on said distillation vessel, a chimney, an annular flue surrounding said distillation vessel and defined vertically by said frusto-conical base and said frusto-conical upper end and a trap communicating with said annular flue and with said chimney, a conduit for leading the gases of distillation from said distillation

vessel to a point beneath said grate and means for drawing in air for combustion of 45 said gases beneath said grate.

5. A continuous distillation device comprising a distillation vessel having a grate, an outwardly flaring frusto-conical perforated base on said distillation vessel resting 50 on said grate, an outwardly flaring frusto-conical upper end on said distillation vessel, a chimney, an annular flue surrounding said distillation vessel defined vertically by said frusto-conical base and said frusto-conical upper end and communicating with 55 said chimney, an air inlet beneath said grate, an annular gas inlet surrounding said air inlet, and a conduit for leading the gases of distillation from said distillation 60 vessel to said air inlet.

6. A continuous distillation device comprising a distillation vessel having a grate, a perforated outwardly flaring frusto-conical base formed upon said vessel and resting upon said grate, a frusto-conical upper end formed upon said vessel, a closed chamber carried by said frusto-conical upper end, an annular flue disposed around said distillation chamber and defined vertically 70 by said frusto-conical base and said frusto-conical upper end, a trap communicating with said annular flue, a chimney communicating with said trap, an annular water chamber surrounding said grate, distillation vessel and annular flue, circulation pipes leading to and from said annular water chamber, an air inlet beneath said grate, an annular gas inlet surrounding said air inlet, and a conduit leading from 80 said closed chamber to said gas inlet.
